INVENTOR
Edward J. Brennan

BY

L. Sanford *W. J. Hanan*
ATTORNEY

UNITED STATES PATENT OFFICE

EDWARD J. BRENNAN, OF HARRISBURG, PENNSYLVANIA, ASSIGNOR TO NASALETS INC., OF NEW YORK, N. Y., A CORPORATION OF NEW YORK

NASAL PELLET

Application filed April 11, 1930. Serial No. 443,288.

This invention relates to a nasal pellet, that is to a device adapted to be inserted into the nasal cavity for use in the treatment of head colds, headaches, sinus trouble, nasal catarrh, and irritated conditions of the nasal and respiratory passages, and the like, and an object of the invention is to provide a pellet which will be practical and efficient for its purpose and which may be manufactured and marketed at reasonable cost.

A more specific object is to provide a pellet which may be easily and conveniently placed in position of use and which will permit of an ample flow of air incident to the breathing of the user.

A further specific object is to provide a pellet which is adapted for carrying a suitable inhalant and which will hold the inhalant out of direct contact with the delicate membranous surface of the nasal cavity.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:

Fig. 1 is a perspective view of a pellet constructed in accordance with this invention and showing the manner of use thereof.

Fig. 2 is an enlarged side elevational view of the pellet appearing in Fig. 1, a portion being broken away and shown in section for illustrating details of construction.

Fig. 3 is a top plan view of the pellet appearing in Fig. 2.

Fig. 4 is an enlarged fragmentary detail view of a portion of the pellet, and

Fig. 5 is a perspective view presented for illustrating a convenient manner of producing the pellets.

The pellet illustrated consists of a thin layer, or sheet, of soft fibrous absorbent ma-

terial, such as absorbent cotton wound or rolled into a pencil-like form, as indicated in Fig. 5, and then cut off in appropriate lengths, as indicated by the dotted lines L—L in Fig. 5, each cut-off section being one of the pellets here contemplated. In producing the rolls or pellets the sheet is wound quite loosely so that numerous air passages as G occur between the layers in the roll, said air passages being intended for permitting a suitable flow of air longitudinally through the pellet incident to the breathing of the user. It is contemplated furthermore that the material, as H, of the sheet itself may be suitably fibrous and porous so that a certain amount of air can percolate therethrough longitudinally of the roll to further increase the air passage area through the roll.

In addition to these air passages the roll is preferably, though not necessarily, formed with an air passage as A centrally therethrough. This air passage may be of any appropriate size desired.

At any time, either before winding the sheet into the roll, or after the roll has been formed and the pellets cut therefrom, a suitable quantity of an appropriate inhalant, preferably in liquid form, may be applied to the material comprising the pellet. This material is suitably absorbent so that it will readily absorb and continue to carry the inhalant, particularly if a liquid inhalant is used, and the air passages above described as extending longitudinally through the pellet will have their walls saturated to a greater or less extent with said inhalant so that air moving through said passages will be laden therewith, it being intended that this laden air shall be beneficial when breathed in by the user.

It is contemplated further that the pellets shall be coated upon their exterior annular surfaces, with a layer as N of suitable soft and pliable material which is of a moisture resisting character calculated to prevent movement of the inhalant outwardly through the exterior surface of the pellet into contact with the delicate membranes

of the nasal cavity of the user. This coating N also serves as a re-inforcing element suitable to hold the pellet approximately in its intended cylindrical shape and to prevent absorbing of the moisture from the nasal cavity into the body of the pellet.

The coating N, while somewhat stiffer than the material from which the body of the pellet is formed it nevertheless is itself 10 suitably soft and pliable so as not to be harsh or injurious to the membranes of the nasal cavity. A thin mixture of starch or gelatine, or the like, may be suitable for this coating.

15 As many changes could be made in this construction without departing from the scope of the invention, as defined in the following claims, it is intended that all matter contained in the above description, or 20 shown in the accompanying drawings, shall be interpreted as illustrative only and not in a limiting sense.

Having thus described my invention, what I claim as new and desire to secure by 25 Letters Patent is:—

1. A device for use in the treatment of colds and the like, said device consisting of a pellet of suitable material containing a quantity of inhalant and being of a size 30 and shape adapting it to be retained by friction with a nasal cavity of the user, and said pellet consisting of a sheet of soft fibrous material loosely wound into a soft roll providing an air passage lengthwise 35 through the roll.

2. A device for use in the treatment of colds and the like, said device consisting of a pellet of suitable material containing a quantity of inhalant and being of a size 40 and shape adapting it to be retained by friction within a nasal cavity of the user, said pellet consisting of a sheet of soft fibrous material loosely wound into a soft roll providing an air passage lengthwise 45 through the roll, and a coating of readily pliable moisture resisting material upon the exterior annular surface of the roll.

3. A device for use in the treatment of colds and the like comprising a pellet 50 formed of a sheet of soft absorbent fibrous material carrying a quantity of inhalant and loosely wound into a substantially cylindrical roll, the successive layers of said roll being spaced to provide a plurality of air passages extending longitudinally of the roll.

4. A device for use in the treatment of colds and the like comprising a pellet 55 formed of a sheet of soft absorbent fibrous material carrying a quantity of inhalant and loosely wound into a substantially cylindrical roll, the successive layers of said roll being spaced to provide a plurality of air passages extending longitudinally of the 65 roll and a coating of pliable moisture resist-

ant material on the exterior of cylindrical surface of the roll.

In testimony whereof I affix my signature.

EDWARD J. BRENNAN.
